(57) CLAIM

The ornamental design for a baby bouncer, as shown and described.

DESCRIPTION

FIG. 1 is a top perspective view of a baby bouncer, showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top perspective view thereof with a restraint released;

FIG. 9 is a front view thereof with the restraint released;

FIG. 10 is a top perspective view thereof with no restraint;

FIG. 11 is a front view thereof with no restraint;

FIG. 12 is a top view thereof with no restraint;

FIG. 13 is a rear perspective view thereof; and,

FIG. 14 is a rear perspective view thereof.

The long-dash broken lines and short-dash broken lines, shown along the seams of the seat fabric, the mesh, the seat insert, and the restraint of the baby bouncer, represent stitching and are not parts of the claimed design. The other broken lines in the drawings illustrate the mesh and portions of the baby bouncer that form no part of the claimed design.
